AUTOMATIC STOP DRAIN VALVE

Joe Arthur Crista, Carlsbad, N. Mex.

Application March 11, 1935, Serial No. 10,367

5 Claims. (Cl. 137—21)

This invention relates to a drain valve and has relation more particularly to a valve for use in connection with a railway tank car.

It is an object of the invention to provide a valve of this kind which automatically closes upon movement of the car during the time of unloading and also to provide a valve to allow the tank to be emptied without removing the dome cap and thus avoiding hazard of fire and possible explosion due to exposing a large area of tank interior to the atmosphere.

Another object of the invention is to provide a valve of this kind which substantially eliminates pilfering of the tank content.

15 The invention consists in the details of construction and in the combination and arrangement of the several parts of my improved drain valve whereby certain important advantages are attained and the device rendered simpler, less expensive and otherwise more convenient and advantageous for use, as will be hereinafter more fully set forth.

The novel features of my invention will hereinafter be definitely claimed.

25 In order that my invention may be the better understood, I will now proceed to describe the same with reference to the accompanying drawings, wherein:—

Figure 1 is an enlarged fragmentary view partly in section and partly in elevation and also of a diagrammatic character illustrating a valve and its associated parts constructed in accordance with an embodiment of my invention and in applied position;

30 Figure 2 is a fragmentary view partly in section and partly in elevation illustrating a means whereby manual operation of the valve may be accomplished;

Figure 3 is a view also partly in section and partly in elevation and of a diagrammatic character illustrating a valve and its associated parts constructed in accordance with an embodiment of my invention and in applied position.

35 In the embodiment of my invention as illustrated in Figures 1 and 2, T denotes a tank such as comprised in a tank car and which includes a conventional dome D. The lower or bottom wall of the tank T is provided with a drain opening 1 which discharges into a drain pipe 2 of desired length and depending from the tank T. At a predetermined point intermediate its ends this pipe 2 has disposed circumferentially therearound a groove 3 whereby the pipe 2 is materially weakened at such point so that the pipe 2 or 40 housing as it may be called may readily break.

Readily insertible within the outer end of the pipe or housing 2 is an end portion of a carry-off line 4 which may be of any length desired and of any preferred type. The outer end portion of the pipe or housing 2 is provided with the peripheral threads 5 to permit the application of a cap thereto after the line 4 has been removed, and which is particularly desirable when the car is in transit. The upper portion of the pipe or housing 2 is formed to provide an internally directed flange 6 to provide a support for a valve seat 7.

Coacting with this seat 7 is a valve member 8 which in its opening movement travels toward the tank T. This valve member 8 is fixed to 15 an end portion of a rod 9 which extends inwardly of the tank and, as illustrated in Figure 1, extends up into the dome D. The upper portion of the rod 9 has threaded thereon a nut or head 10 with which engages an end portion of a coil spring 11 encircling the rod 9 above said nut and also having contact with a guide bracket 12 for the upper portion of the rod 9 and which bracket, as herein disclosed, is carried by and extends inwardly from the side wall of the dome D.

20 The valve member 8 has a part depending therefrom which constitutes a plunger 14 snugly fitting and working within the cylinder 15. This cylinder 15 is carried by a spider 16 at a point between the flange 6 and the weakened portion 3 of the pipe or housing 2. The cylinder 15 in advance at all times of the plunger 14 has in communication therewith a line or conduit 17 which extends out through the side wall of the pipe or housing 2 and leads to a suitable source of air under pressure, such source being herein disclosed as a tank 18 which is to be permanently attached to a car at any convenient place.

25 Leading from the tank 18 is a flexible pipe line 19 which is provided at its outer extremity with a valve structure 20 which is normally closed. This line 19 is of a length to be readily thrown across a rail of a trackway fore and aft of a wheel of the car during an unloading operation so that if, during such unloading operation, the car should start to travel in either direction the wheel W of the car will sever the line 19 thus immediately relieving the pressure within the tank 18. This release of pressure will permit the immediate closing of the valve member 8 under 30 the action of the spring 11.

35 The valve structure 20 is of a type to permit the same to be readily employed with a prime source of air pressure when it is desired to move the valve member 8 into open position to deliver 35

or drain out the content of the tank T. This pressure passes through the tank 18 and line 17 to the cylinder 15 and moves the plunger 14 outwardly to unseat the valve member 8. This pressure is built up within the tank 18 after which the valve structure 20 is closed and disconnected from the prime source of air pressure. When it is desired to have the valve member 8 seat, this valve structure 20 is opened 10 whereby is released the pressure within the cylinder 15.

To assure the discharge of the content of the tank T said tank has in communication therewith through the top wall of the dome D a vent 15 21 which is under control of a conventional valve 22.

When it is desired to manually move the valve member 8 into open position, the top 23 of the dome D will be removed and a nut 24 threaded 20 upon the upper portion of the rod 9 down into contact with the bracket 12. This nut 24 is intended to be applied at the point of unloading but not to be carried during transit.

The structure as hereinbefore described has to 25 be what is termed a permanent structure. In Figure 3 is illustrated the embodiment of my invention which may be designated as a temporary structure wherein the tank T' has depending therefrom a conventional drain housing 30 or pipe 25 flow through which being normally closed by a valve 26. The outer portion of the housing or pipe 25 is adapted to have threaded therein an end portion of a tubular member 27 of desired length. This tubular member 27, as 30 herein disclosed, is sectional and has its adjacent ends suitably coupled, as at 28, such coupling including a member having a spider 29 intersecting the tubular member and which provides a guide for an elongated sleeve 30. The 35 outer end of this sleeve 30, as herein disclosed, is closed by a cap 31 which is placed into direct contact from below with the valve member 26. The opposite end portion of this sleeve 30 has threaded therein an end portion of a plunger 32 40 whereby the desired contact of the sleeve 30 with the valve 26 may be assured. The outer end portion of the tubular member 27 threads into an end portion of a casing 33, the opposite end portion of which having a threaded opening 34 45 to permit the connection with said casing of a delivery or carry-off line. This casing 33 is intersected by a spider 35 which provides a mounting for a cylinder 36 in which snugly engages the end portion of the plunger 32 remote from 50 the sleeve 30. This cylinder 36 in advance of the plunger 32 has in communication therewith a line 37 leading to a tank 38 and which tank 38 has in communication therewith a flexible line 39 to provide means for connection with a 55 prime source of air under pressure. The operation of this embodiment of my invention is in accordance with that of the first embodiment hereinbefore set forth and, therefore, it is not believed necessary that a detailed explanation of the operation of this temporary type be given.

From the foregoing description it is thought to be obvious that a drain valve constructed in accordance with my invention is particularly well adapted for use by reason of the convenience and 60 facility with which it may be assembled and operated, and it will also be obvious that my invention is susceptible of some change and modification without departing from the principles and spirit thereof and for this reason I do not 65 wish to be understood as limiting myself to the 70 75

precise arrangement and formation of the several parts herein shown in carrying out my invention in practice except as hereinafter claimed.

I claim:

1. A valve structure for use within a discharge 5 housing in communication with a tank, said structure including a valve to normally close the flow out through the housing, a cylinder within the housing, a piston working within the cylinder and coacting with the valve to move the valve into open position upon movement of the piston in one direction, an air pressure tank in communication with the cylinder so that the pressure within the tank will effect such movement of the piston to open the valve member, a rod carried by 10 the valve member to extend inwardly of the tank, a guide bracket for said rod for position within the first tank, an enlargement carried by the rod, and a spring interposed between the bracket and enlargement of the rod and placed under tension 15 when the valve is moved into open position to return the valve to closed position upon reduction of pressure in the air pressure tank.

2. A valve structure for use within a discharge 20 housing in communication with a tank, said structure including a valve to normally close the flow out through the housing, a cylinder within the housing, a piston working within the cylinder and coacting with the valve to move the valve into open position upon movement of the piston in one direction, an air pressure tank in communication with the cylinder so that the pressure within the tank will effect such movement of the piston to open the valve, a rod carried by the valve 25 to extend inwardly of the tank, a guide bracket for said rod for position within the first tank, an enlargement carried by the rod, a spring interposed between the bracket and enlargement of the rod and placed under tension when the valve is moved into open position to return the valve to closed position upon reduction of pressure in the air pressure tank, and means carried by the rod for coaction with the bracket to move the rod independently of the piston to open the valve.

3. A valve structure for use in connection with 30 a discharge housing including a valve member for normally closing the flow out through the housing, a cylinder within the housing, a piston working within the cylinder, a member operating upon movement of the piston in one direction to adjust the valve member into open position, said member comprising a plunger and a sleeve, the plunger engaging within the sleeve, said plunger and sleeve having coacting means to permit relative 35 adjustment thereof one lengthwise of the other, and means for admitting fluid under pressure within the cylinder to impose movement on the piston for moving the valve member into open position.

4. A valve structure for use in connection with 40 a discharge housing including a valve member for normally closing the flow out through the housing, a cylinder within the housing, a piston working within the cylinder, a member operating upon movement of the piston in one direction to adjust the valve member into open position, said member comprising a plunger and a sleeve, the plunger threading into the sleeve, and means for admitting fluid under pressure within the cylinder to 45 impose movement on the piston for moving the valve member into open position.

5. A valve structure adapted to be secured 50 about the drain opening on tanks mounted on wheeled vehicles, said structure comprising a casing 55 having a passage therethrough, a valve seat 60

in the casing, a valve normally resting on said seat, a cylinder supported in the casing, said valve having a piston working in said cylinder, a fluid pressure tank in communication with the cylinder, a flexible hose or pipe having one end in communication with said tank and a valve at the free end thereof, said pipe or hose being adapted to be connected with a source of fluid

pressure for unseating said valve, said pipe or hose being of such length, that when unsupported it will normally fall in the path of the wheels of the vehicle so that in case the vehicle should be moved inadvertently the hose or pipe will become mutilated and thus release the fluid pressure and permit the valve in the casing to close.

JOE ARTHUR CRISTA.
